UNITED STATES PATENT OFFICE.

EDMUND H. LUNKEN, OF DENVER, COLORADO, AND HENRY RITTER, OF DELHI, OHIO, ASSIGNORS TO THE LUNKENHEIMER COMPANY, OF CINCINNATI, OHIO.

GRAPHITE LUBRICATOR.

SPECIFICATION forming part of Letters Patent No. 653,027, dated July 3, 1900.

Application filed November 20, 1899. Serial No. 737,616. (No model.)

To all whom it may concern:

Be it known that we, EDMUND H. LUNKEN, residing at Denver, Arapahoe county, Colorado, and HENRY RITTER, residing at Delhi, 5 Hamilton county, Ohio, citizens of the United States, have invented certain new and useful Improvements in Graphite Lubricators, of which the following is a full, clear, and exact description, reference being had to the accompanying drawings, forming part of this specification.

Our invention relates to that class of lubricators employing a powdered lubricant, such as graphite, either dry or mixed with oil; and 15 it has for its object the improved construction of the same whereby the simplicity and efficiency of the lubricator are increased and whereby an even discharge of the lubricant is insured.

20 The novelty of our invention will be hereinafter set forth, and specifically pointed out in the claims.

In the accompanying drawings, Figure 1 is a sectional side elevation through the axis of the lubricator embodying our invention. Fig. 2 is a corresponding view at right angles to Fig. 1. Fig. 3 is a side elevation in detail at the feeding-neck of the lubricator looking toward the right of Fig. 1.

30 The same letters of reference are used to indicate identical parts in all the figures.

The body of the lubricator is composed of a cup-shaped receptacle A, into the interiorly-threaded top of which is screwed a cap B, having a central boss b, into which is screwed a plug-valve c, the lower end of which passes below and is intended to cover or expose one or more openings or perforations d through the boss or cap B and which open into a central tube e, the upper end of which is screwed into the under side of the cap and communicates with the opening into which the screw-plug c enters.

The lower end of the cup A has a funnel-shaped discharge f, controlled by a plug-valve or stop-cock C, and it has a lower outlet-passage g, opening into a chamber h, having on opposite sides sight-feed disks i, of glass, held in place by threaded thimbles j, screwed into 45 the apertures which the sight-feed glasses occupy. Beneath the chamber h is an aperture

k through the threaded neck l of the lubricator, and by which latter it is screwed into the pipe or other bearing to be lubricated.

This lubricator is designed particularly for 55 use on explosive-engines, and the duct or ducts d being opened to the extent required by screwing up the plug c and the cock C being opened to the required degree whenever a vacuum is caused in the cylinder of the engine a charge of the graphite is drawn out of the cup through the channels g h k into the cylinder, and its passage can readily be observed through the sight-feed glasses i. The lubricator so far described would form a very 60 efficient lubricator for this class of work, for by regulating the admission of air through the duct or ducts d and tube e down to the bottom of the graphite just at its point of discharge an exact amount of graphite will be 65 fed whenever a vacuum is caused beyond the outlet k, as occurs in an explosive-engine; but to render the lubricator more perfect in its adjustments, so that the cock C may be 70 shut off to stop the feed at any time and then 75 may be opened again to the exact point it previously occupied to permit the required discharge at each suction, we provide a rib or wing m, Figs. 1 and 3, on the cock, with which a set-screw n, engaging through the neck of 80 the lubricator, bears in such manner that by turning the set-screw in or out it forms a regulating-stop against which the wing m strikes to arrest the cock at that point. Thus the screw n may be so set that the cock can only 85 be turned a quarter-open, a half-open, or three-quarters open, or any degree of opening from its closed position to its entire open position, as will be readily understood, so that the engineer having once got the set-screw n 90 set to suit the feed requisite for the duty of his engine he may shut it off at any time when the engine ceases to run, and when he starts it up again he can open the cock until it is arrested by the set-screw, and thereby know 95 that the parts are in perfect adjustment.

Having thus fully described our invention, we claim—

1. In a lubricator, the combination of a cup for the lubricant having a funnel-shaped discharge end, a tube passing down through the cup and opening into the funnel-shaped dis-

charge end, a cover or cap for the cup having an orifice therethrough into said tube and a cock in the cover for regulating the size of said orifice, substantially as described.

5 2. In a lubricator, the combination of a cup for the lubricant having a funnel-shaped discharge end, a regulating-cock therein for the discharge of the lubricant, a sight-feed aperture below said regulating-cock, a tube passing down through the cup and opening into the

funnel-shaped discharge end, a cover or cap for the cup having an orifice therethrough into said tube and a cock in the cover for regulating the size of said orifice, substantially as described.

EDMUND H. LUNKEN.
HENRY RITTER.
